UNITED STATES PATENT OFFICE.

WALLACE B. WOLFF, OF CHICAGO, ILLINOIS.

SLICING MACHINE.

Application filed December 22, 1924. Serial No. 757,307.

To all whom it may concern:

Be it known that I, WALLACE B. WOLFF, a citizen of the United States, residing at Chicago, in the county of Cook and State of Illinois, have invented a certain new and useful Improvement in Slicing Machines, of which the following is a specification.

My invention relates to a meat slicing machine and particularly to a slicing machine in which the slicing mechanism is housed in an outer shell or covering of vitreous white enamel. One object of the invention is to permit the protection of a slicing machine structure by vitreous enamel covering. Another object is to permit the application of such a covering without cracking or damaging the enamel in the course of manufacture of the machine. Another object is to permit the application of a vitreous covering to a slicing machine without affecting the main slicing machine frame or the alignment and accuracy of its bearings. Other objects will appear from time to time in the course of the specification and claims.

I illustrate the invention more or less diagrammatically in the accompanying drawings, wherein—

Figure 1 is a plan view;

Figure 2 is a side elevation and skeleton view;

Figure 3 is an end elevation and skeleton view;

Figure 4 is a section on the line 4—4 of Figure 1;

Figure 5 is a section on the line 5—5 of Figure 1; and

Figure 6 is a section on the line 6—6 of Figure 1.

Like parts are indicated by like characters throughout the specification and drawings.

A is any suitable upper housing element which is provided with a downwardly extending circumferential flange 'A¹' adapted to overhang and overlap the upper edge A² of the lower housing member A³.

The housing formed by the two overlapping members A and A³ entirely encloses the driving and frame mechanism of the slicing machine but is apertured, as will later appear, to permit the penetration of the upwardly or outwardly projecting members of the slicing machine, and to permit the securing of the housing elements to the slicing machine frame.

The particular details of the supporting frame and the bearings and working parts need not be described in complete detail. I provide a lower frame member B, to which the lower housing member A³ is secured, for example by means of the bolts B¹ and the nuts B². In practice I find that it is sufficient thus to secure the housing element at four points only. It will be understood that only the sides of the housing A³ are enameled, the bottom being invisible.

B³ is a frame supporting foot adapted to penetrate through the aperture A⁵ of the housing member A³, the aperture being large enough for ample clearance. Where the slicing machine is to be set on a counter, the feet may be provided with the frictional or yielding pads B⁴. It will be understood that there are four of the feet B³, one at each corner of the slicing machine.

All the bearings for the moving parts are mounted in and supported by the frame structure, and the housing is merely a sheathing, with no supporting function.

C, for example, is a bearing for the main drive shaft C¹ and is aligned with an aperture C² in the side of the housing member A³. Through this aperture the inwardly projecting hub C³ of the wheel C⁸ may penetrate, it being understood that the hub is held against rotation in relation to the shaft C¹ by the notch C⁴ which receives the pin C⁵ on the shaft. C⁶ is any suitable securing bolt and C⁷ the nut for drawing the hub down upon the shaft. C⁸ is the usual combined drive and fly wheel integral with the hub C³ and provided with a handle C⁹. The wheel and hub may be finished in vitreous enamel, and if, in the course of securing the hub to the shaft the inner edge of the hub becomes battered or cracked, the defaced enamel will be concealed, since it penetrates through the aperture C² and lies within the housing element A³.

Upwardly projecting from the bearing C is the arm D which is a typical supporting member, for the housing section. It will be understood that a generally similar support member is positioned at each corner of the slicing machine for example the support D¹ shown at the left of Figure 2. Thus the housing member A is supported at its four corners. In order to prevent breakage of the enamel surface I provide a yielding sup-

port which consists of the washer D^2 and the spiral spring D^3 between the support D and the housing member A . Above the housing member is the yielding washer D^4 . D^5 is a track supporting knob which also serves to hold the housing A in position, and is penetrated by the bolt D^6 screw-threaded into the top of the support D . D^7 is a track, round in cross section, connecting and supported by the two similar knobs D^8 . D^9 is a square track extending between the supporting knobs D^{10} which may be similarly secured to upwardly projecting supporting members similar to D and D^1 . The apertures in the member A are large enough to permit ample clearance, but are washed by the knobs.

E is a rotary knife mounted on the knife support E^1 , and driven from the drive shaft C^1 by any suitable driving connection, the details of which form no part of the present invention.

G is a meat supporting carriage adapted to be reciprocated back and forth along the tracks D^7 and D^9 past the effective edge of the knife E , in response to rotation of the shaft C^1 . G^1 is a meat support adapted to be moved along the carriage G toward the knife E , in automatic response to each reciprocation of the carriage G , in order to feed the meat G^2 forward a distance equal to the thickness of each successive slice. G^3 is any suitable clamp for holding the meat in position on the carriage G^1 , and G^4 is a removable meat supporting plate.

It will be understood that the details of the meat carriage form no part of the present invention but are inserted merely to make the function of the entire device understandable.

H is any suitable slice receiving shelf adapted to receive the slices as they are severed by the knife. It is supported, for example on brackets H^1 which are secured, through apertures in the housing A^3 , to the interior frame member for example by bolts H^4 .

J is a base for a knife guard, not herein shown, which may be secured for example by the bolts J^1 , which pass through the aperture J^2 in the housing member A , to the frame projection J^3 .

K is a channel member having the externally projecting flanges K^1 the supporting functions of which need not be considered in detail. It is secured in any suitable manner to the frame projection K^2 which pass through the aperture or indentation K^3 formed in both housing members.

It will be realized that whereas I have shown a practical operative device that nevertheless many changes may be made in the size, shape, number and disposition of parts without departing from the spirit of my invention and that I wish my drawings and description to be taken as in a broad

sense diagrammatic rather than as limiting me to the specific form of apparatus therein described and shown.

The use and operation of my invention are as follows:

The general mechanism of the slicing machine herein shown is old and needs no extended discussion. The rotation of the main shaft C^1 , whether through the manual wheel C^2 or through a connection to some other power source, serves through any suitable gearing, to rotate the knife E and also to reciprocate the carriage G , along the tracks D^7 and D^9 , past the cutting edge of the knife. The carriage G^1 is moved to the left, as shown in Figure 1, a thickness equal to the desired slice, in automatic response to each reciprocation.

It has in the past been the practice to paint the slicing machine housing, and to finish off certain portions in metal. For sanitary reasons, as well as for ornamental appearance, it is highly desirable to finish slicing machines in white enamel. It has heretofore been practically impossible to do this, for the following two reasons. In the first place, the enameling of metal necessitates a heat treatment of the metal which may raise its temperature as high as from 1700 to 2000 degrees Fahrenheit. If the various parts have been machined, the effect of the heat treatment is to so warp and deform the castings as to render them absolutely unusable. On the other hand, if the parts are enameled before they are machined, the machining will crack and break the enamel on so many castings as to render the cost of manufacture prohibitive.

I avoid both objections by constructing a slicing machine with an interior frame structure in which the various rotating parts are mounted. The structure is entirely independent of the sanitary enamel housing, and therefore is in no way affected by the heat treatment of the housing. For the supporting structure I provide a two part housing of white enameled metal, which consists of an upper member A and a lower member A^3 . The upper member rests upon four upwardly projecting arms of which D and D^1 are typical. These arms support the knobs D^5 and D^{10} to which the tracks D^7 and D^9 are secured. Since the enamel is liable to crack and break, if subjected to shock or strain, I mount the housing member A yieldingly by placing between it and the arm D^1 the washer D^2 and the spiral spring D^3 . Beneath the knob D^6 or D^{10} and above the member A , I position the yielding washer D^4 . Thus when the bolt D^6 is tightened, a yielding washer presses the member A downwardly against a coil spring, and not only is the member A freed from the minor shocks of operation, but it is positively cushioned. The clearance is so great that whereas the knob D^5 or D^{10}

overhangs the circumference of the aperture, entirely masking it, at no point is its inner edge in contact with the knob. This permits adjustment of the housing and allows for variations in size, due to the heat treating.

In order to prevent positive engagement between the two housing elements, I make the upper housing A outwardly overlap and overhang as at A¹ the upper edge A² of the lower housing member A³. The lower member, like the upper, is fastened to the frame at four points, by the bolts B¹ and the nuts B². A cushioning is unnecessary, since the bottom of the housing is not enameled, being invisible. The clearance between the aperture A⁵ and the stud or foot B³ is sufficient to permit minor variations in the size of the heat treated housing, as is the case with the apertures of the upper housing.

Both housings are apertured wherever necessary to admit the passage of outwardly projecting members, and these members are without exception secured, not to the housing elements, but to the frame within the housing.

I claim:

1. A slicing machine comprising in part a drive shaft and a rotary knife, a frame adapted to support the moving and rotating parts, and a housing for said frame, structurally independent thereof and removably secured thereto, comprising an upper and a lower housing member, the upper member overhanging and overlapping the lower member but out of contact therewith.

2. In a slicing machine an enclosed supporting frame, bearing members, supported by said frame, for all the moving parts of said slicing machine, and a housing, structurally separate from said frame, and yieldingly mounted thereon.

3. In a slicing machine an interior supporting frame, bearing members, supported by said frame, for all the moving parts of said slicing machine, and a housing, structurally separate from said frame, and secured thereto, comprising an upper housing member and a lower housing member, the upper housing member overlapping the lower, about the sides of the frame.

4. In a slicing machine an interior supporting frame, bearing members, supported by said frame, for all moving parts of said slicing machine, and a housing, mounted on said frame, the upper section of said housing being independently secured to the top of said frame and the lower part of said housing being independently secured to the bottom of said frame, said housing members being structurally separate.

5. In a slicing machine an interior supporting frame, bearing members, supported by said frame for all moving parts of said machine, and a sectional housing mounted on said frame, the various sections of said

housing being independently secured to said frame.

6. In a slicing machine an interior supporting frame, bearing members, supported by said frame for all moving parts of said machine, and a sectional housing mounted on said frame, the various sections of said housing being independently secured to said frame, and out of contact with each other.

7. In a slicing machine an interior supporting frame, bearing members, supported by said frame, for all the moving parts of said slicing machine, a housing of metal coated with a vitreous enamel, structurally separate from said frame, and secured thereto, comprising an upper housing element and a lower housing element, the upper element outwardly overlapping and overhanging the lower.

8. In a slicing machine an interior supporting frame, bearing members, supported by said frame, for all the moving parts of said slicing machine, a housing of metal coated with a vitreous enamel, structurally separate from said frame, and secured thereto, comprising an upper housing element and a lower housing element, the upper element outwardly overlapping and overhanging the lower, the upper element being yieldingly mounted on the frame.

9. In a slicing machine an interior supporting frame, bearing members, supported by said frame, for the moving parts of said slicing machine, a housing of relatively breakable material, structurally separate from said frame, and yieldingly mounted thereupon.

10. In a slicing machine an interior supporting frame, bearing members, supported by said frame, for all the moving parts of said slicing machine, and a housing secured to said frame, such housing being structurally separate from said frame and out of contact therewith except at the points of attachment.

11. In a slicing machine an interior supporting frame, bearing members, supported by said frame, for all the moving parts of said slicing machine, and a housing secured to said frame, such housing being structurally separate from said frame and out of contact therewith except at the points of attachment, comprising a plurality of sections each independently secured to said frame.

12. In a slicing machine an interior supporting frame, bearing members, supported by said frame, for all the moving parts of said slicing machine, and a housing secured to said frame, such housing being structurally separate from said frame and out of contact therewith except at the points of attachment, comprising an upper and a lower section, the upper section overhanging and overlapping the lower section.

13. In a slicing machine an interior sup-

porting frame, bearing members, supported by said frame, for the moving parts of said machine, a housing of relatively breakable material mounted on said frame, apertures in said housing to permit the projection therethrough of supporting frame members, said apertures being substantially larger than the members which project therethrough, and means for masking said apertures.

14. In a slicing machine, an interior supporting frame, bearing members, associated with said frame, for all the moving parts of said slicing machine, and a housing secured 15 to said frame, and structurally separate and

removable therefrom and out of contact therewith except at a relatively small number of points of attachment, said housing comprising an upper and a lower section, said sections being out of contact with each other and being independently mounted upon the frame, the upper section being yieldingly mounted in relation to the frame, the lower section being fixed in relation thereto. 20 25

Signed at Chicago county of Cook and State of Illinois, this 12th day of December 1924.

WALLACE B. WOLFF.
